UNITED STATES PATENT OFFICE

WILLIAM R. MATTHEWS AND ETHELBERT JONES, OF SPOKANE, WASHINGTON

DESIGN FOR A BUILDING FRONT

Application filed November 19, 1930. Serial No. 37,726. Term of patent 14 years.

To all whom it may concern:

Be it known that we, WILLIAM R. MATTHEWS and ETHELBERT JONES, citizens of the United States, residing at Spokane, in Spokane County, and State of Washington, have invented a new, original and ornamental Design for Building Fronts, of which the following is a specification, reference being had to the accompanying drawings, forming a part thereof.

The design provides for a building front, constructed of any suitable material and color combination.

Figure 1 is a plan view of the building front.

Figure 2 is a cross section of Figure 1 taken on line 2—2.

Figure 3 is a view in cross section of Figure 1 taken on line 3—3.

We claim:

The ornamental design for a building front substantially as shown and described.

WILLIAM R. MATTHEWS.
ETHELBERT JONES.
